UNITED STATES PATENT OFFICE.

JOHN H. CULLOM, OF ROSEMARY, NORTH CAROLINA.

GONG-RINGING APPARATUS.

Application filed July 15, 1922. Serial No. 575,176.

To all whom it may concern:

Be it known that I, JOHN HENRY CULLOM, a citizen of the United States, residing at Rosemary, in the county of Halifax and State of North Carolina, have invented certain new and useful Improvements in Gong-Ringing Apparatus, of which the following is a specification, reference being had to the accompanying drawings.

10 This invention relates to improvements in a gong ringing apparatus, and more particularly to a device of this character actuated indirectly by the striking mechanism of a clock.

15 An important object of the invention is to provide a device of this character which may be very readily and cheaply constructed and which is extremely durable in service.

20 A further object of the invention is to provide an actuating mechanism or attachment for the gong ringing device which may be readily attached to a convenient clock for operating the same and the installation of which will not require the services of a 25 skilled mechanic.

25 A still further object of the invention is to provide a gong ringing apparatus in which the use of springs is dispensed with in order that a device may be provided which 30 will be entirely dependable.

35 These and other objects I attain by the construction and arrangement shown in the accompanying drawings wherein for the purpose of illustration is shown a preferred embodiment of my invention and wherein like reference characters designate like parts throughout.

On the drawings:

40 Figure 1 is a sectional view illustrating a gong ringing apparatus constructed in accordance with my invention;

Figure 2 is a detail view partially in section showing the mounting of the armatures;

45 Figure 3 is a vertical sectional view taken through the apparatus; and

Figure 4 is a detail view showing the clock work actuated switch.

50 Referring now more particularly to the drawings, the numerals 10 and 11 indicate substantially horizontal, vertically spaced support members, these members being spaced by spacing elements 12 arranged pref-

erably at the ends thereof. The upper ends of these spacing elements extend through the upper support member 10 and form means for attaching to this upper support member upwardly extending braces 13 which support a gong 14. Immediately beneath the gong 14 the supports 10 and 11 are provided with vertically aligned openings 15 through which is directed a shaft 16 which is counterweighted at its upper end, as indicated at 17, the counterweight forming a clapper for the gong.

Secured to the lower support 11 at opposite sides of the shaft 16 and extending upwardly therefrom are electromagnets 18 which are connected in series. While a single electromagnet of sufficient strength arranged at each side of the shaft may be employed, I prefer to employ a pair of these electromagnets arranged at each side of the shaft. Extending downwardly from the under surface of the upper support 10 intermediate the vertical axes of the electromagnets is a 75 guide 19, a guide being arranged in each pair of electromagnets. Since the mechanism at each side of the shaft 16 is similar, that at but one side of the shaft will be herein-after described. Upon this guide 19 is slidably mounted a sleeve 20, to the lower end of which is secured an armature 21 for the corresponding pair of magnets. A second guide 22 extends downwardly from the support 10 and has its lower end arranged beneath the lowermost point of travel of the armature 21, this guide 22 extending through the armature 21 and preventing rotation of the sleeve 20 thereof upon the guide 19.

Extending downwardly from the support 90 10 is provided an adjustable pivot member 23, the lower end of which is pivotally connected intermediate the ends of a lever 24. One end of the lever 24 is furcated and the furcations slotted to receive pins 25 extending outwardly from opposite sides of the sleeve 20. The opposite end of the lever 24 is provided with an angular portion 26 having an opening 27 therein through which extends one end of a horizontal bar 28 secured 100 intermediate its ends to the shaft 16.

The weight of the counterweight or clapper 17 is sufficient to counterbalance the weight of the armature and sleeve 20 and

accordingly the shaft 16 normally assumes a lowered position with the armatures 21 raised above their magnets. When, however, the magnets are energized, the armatures 5 are drawn downwardly. While a single armature with its magnets may be employed for operating the shaft 16, the tendency to move the shaft 16 to one side and the resulting binding of the shaft in its guide openings renders the operation of the device uncertain and I accordingly prefer the construction herein illustrated.

The device may be employed in conjunction with a clock having a striking mechanism by connecting one terminal of the magnet series with the clock works as by wire 29 and employing a contact switch such as shown in Figure 4 for the other terminal of the series. This contact switch comprises an 15 arm 30 having one end thereof furcated, as indicated at 31, and the other end having pivotally connected thereto a lever 32. The arm 30 is provided with a stop member 33 against which one end of the lever 32 is held 20 engaged by the arm 30 and lever 32 respectively. The end of this lever is arranged to project into the control train of the striking mechanism and more particularly into the path of movement of the stop pins 37 of 25 the control wheel 38 thereof.

As is well known to those familiar with the art, these pins control the striking movement and act to stop the striking in the ordinary operation of the clock. When the lever 32 has its end engaged by a pin 37, an electrical connection is completed through the clock works to the arm 30 and through the arm 30 to the binding member 39 by means of which the arm 30 is secured to a suitable 30 support. It will be noted that the arm 30 being bifurcated for a considerable length at 31, the arm and lever may be adjusted toward or away from the center of the control wheel 38 to adjust the length of contact. 35 The lever 32 yields against the action of a pin 37 permitting passage of the pin and upon passage of the pin again assumes its normal position against the stop 33 and with its end arranged in the path of the next stop 40 pin of the control wheel. The clock having the striking mechanism may be arranged either in a tower 40 forming a support for the striking mechanism or may be arranged at a remote point as desired. Furthermore, 45 the striking mechanism may, if desired, include in series with the magnets a light 41 which is flashed upon each actuation of the gong. The gong ringing apparatus will be 50 preferably enclosed within a suitable weather-tight frame from the upper end of which supports 42 may be extended for use in maintaining in position a hood 43 for excluding rain, snow, sleet and the like from the gong and the opening through which 55 the shaft 16 and clapper 17 extend. The

light 41 may be located within the above mentioned frame or at any other desired point to the gong striking or clockwork apparatus as desired.

From the foregoing it is believed to be 70 obvious that a gong ringing apparatus constructed in accordance with my invention is particularly well adapted for the purpose for which it is intended for the reason that the construction of the same is such that the 75 use of springs is substantially eliminated and for the reason that the structure thereof is so simple that there is practically no working part which is susceptible to wear. It will furthermore be obvious that the construction hereinbefore set forth is capable 80 of some change and modification without materially departing from the spirit of my invention and I accordingly do not limit myself to such specific structure except as 85 hereinafter claimed.

I claim:—

1. In gong ringing apparatus, the combination with a gong, of spaced supports arranged beneath the gong, a shaft guided by 90 said supports and directed toward the gong and having a counter-weight normally holding the same in lowered position, said counter-weight constituting a clapper for engaging the gong, a member paralleling 95 said shaft, electromagnetic means for longitudinally shifting the member, and a lever pivoted intermediate its ends, having one end thereof operatively connected to said member and the other end thereof operatively connected to the shaft.

2. In a gong ringing apparatus, the combination with a gong, of spaced supports arranged beneath the gong, a shaft guided by 100 said supports and directed towards the gong and having a counter weight normally holding the same in lowered position, said counter weight constituting a clapper for 105 engaging the gong, electromagnetic means for elevating the shaft against the action of the counter weight including an electromagnet secured to the lowermost of said supports, a guide extending downwardly from the uppermost support toward the electromagnet, 110 a sleeve mounted upon the guide and provided at its lower end with an armature for coaction with the electromagnet, and a lever pivoted intermediate its ends and having one end thereof slidably and pivotally engaged with the sleeve and the other end 115 thereof operatively engaged with the shaft.

3. In a gong ringing apparatus, the combination with a gong, of spaced supports arranged beneath the gong, a shaft guided by 120 said supports and directed towards the gong and having a counter weight normally holding the same in lowered position, said counter weight constituting a clapper for 125 engaging the gong, electromagnetic means for elevating the shaft against the action of 130

the counter weight including a cross arm secured to said shaft, levers having their ends slidably and pivotally engaged with said cross arm, said levers being pivoted intermediate their ends, an electromagnet secured to one of said supports beneath the free end of each of said levers, and an arma-

ture for each of said electromagnets supported by the free end of each of said levers.

10

In testimony whereof I hereunto affix my signature.

JOHN H. CULLOM.
